UNITED STATES PATENT OFFICE.

WILLIAM A. DE SCHAUM, OF DETROIT, MICHIGAN.

DESIGN FOR A RADIATOR.

45,217.

Specification for Design.

Patented Feb. 3, 1914.

Application filed November 15, 1913. Serial No. 801,266. Term of patent 7 years.

To all whom it may concern:

Be it known that I, WILLIAM A. DE SCHAUM, a citizen of the United States of America, residing at Detroit, in the county of Wayne and State of Michigan, have invented a certain new, original, and ornamental Design for Radiators, of which the following is a specification, reference being had therein to the accompanying drawings, forming part thereof, in which—

Figure 1 is a perspective view of a radi-

ator, showing my new design; Fig. 2 is a side elevation thereof, and Fig. 3 is a plan view.

I claim:

The ornamental design for a radiator, substantially as shown.

WILLIAM A. DE SCHAUM.

Witnesses:

JAMES P. BARRY,
ARTHUR D. PULVER.
